TILE OR SIMILAR ARTICLE

Roberto Juan Claudio Mattiello, Andonaegui 1170,
Buenos Aires, Argentina

Filed Feb. 11, 1965, Ser. No. 83,774

Term of patent 14 years

(Cl. D18—2)

FIG. 1 is a top plan view of a tile embodying my new design, the dotted lines showing of several associated tiles being for illustrative purposes only.

FIG. 2 is a perspective view of a tile embodying my new design.

FIG. 3 is an edge elevational view as viewed from the top of the tile in FIG. 2 embodying my new design.

FIG. 4 is a side elevational view from the side of the tile in FIG. 2 embodying my new design.

I claim:

The ornamental design for a tile or similar article, substantially as shown and described.
